(57) **CLAIM**

The ornamental design for a replacement leg segment for warehouse rack, as shown and described.

DESCRIPTION

FIG. 1 is a perspective view of the rear of a replacement lower leg segment for warehouse rack, showing my new design;

FIG. 2 is a rear elevational view, thereof;

FIG. 3 is an elevational view of one side, thereof; the other side elevational view being substantially a mirror image, thereof;

FIG. 4 is a front elevational view, thereof;

FIG. 5 is a top plan view, thereof;

FIG. 6 is a bottom plan view, thereof; and,

FIG. 7 is a right front perspective of the article, taken to a reduced scale, the broken line representation of an opposing rack leg and the associated brace members being included solely for illustrative purposes, forming no part of the claimed design.
